UNITED STATES PATENT OFFICE.

SAMUEL W. M. KOLLOCK, OF SEATTLE, WASHINGTON, ASSIGNOR, BY DIRECT AND MESNE ASSIGNMENTS, OF ONE-FOURTH TO GEORGE L. KOLLOCK, ONE-FOURTH TO ROBERT P. MARTIN, AND ONE-FOURTH TO WILFRED BARAN, ALL OF SEATTLE, WASHINGTON.

MECHANICAL MOVEMENT.

1,349,283.

Specification of Letters Patent. Patented Aug. 10, 1920.

Application filed July 12, 1918. Serial No. 244,658.

To all whom it may concern:

Be it known that I, SAMUEL W. M. KOLLOCK, a citizen of the United States, residing at Seattle, in the county of King and State of Washington, have invented new and useful Improvements in Mechanical Movements, of which the following is a specification.

The object of the invention is to provide an electrically operated hammer adapted for actuating different kinds of tools such as a chisel, riveting punch and the like and having its elements so mounted and related as to insure efficiency and durability with facility of control by the operator.

Further objects and advantages will appear in the following description, it being understood that changes in form, proportion and details of the illustrated and preferred embodiment thereof may be resorted to, within the scope of the appended claims, without departing from the spirit of the invention.

In the drawings:—

Figure 1 is a longitudinal sectional view of the apparatus;

Fig. 2 is a similar view showing the parts in a plane at right angles to that of Fig. 1.

Fig. 3 is a transverse section on the plane indicated by the line 3—3 of Fig. 1.

Figs. 4 and 5 are detailed side and edge views of a slightly modified form of hammer or plunger yoke and related tappet elements.

Figs. 6 and 7 are detailed side and edge views respectively of another slightly modified form of plunger or hammer and yoke with the tappet elements.

Within a suitable casing 10, which may be tubular as shown and to one end of which is attached a handle or grip 11, is arranged a motor having a field or stator 12 and the armature or rotor 13, the spindle 14 of the latter being mounted in transverse heads 15 and 16. The terminals 17 and 18 may be attached to any suitable source of energy and arranged in the circuit formed by the conduits 19. A plug switch 20 arranged within convenient reach of a hand grasping the grip.

To the spindle of the rotor which carries a ventilating fan 21 is attached a beveled pinion 22 meshing with a gear 23 of which the shaft 24, suitably mounted transversely

in the casing also carries a pinion 25 meshing with peripheral gear teeth on the tappet 55 wheel or disk 26 which is arranged in operative relation with a yoke 27 on a hammer or plunger 28. The plunger is mounted for reciprocatory motion in a bearing ring 29 and has a terminal washer 30, while between 60 said bearing ring and washer is located a plunger actuating spring 31.

In the construction illustrated in Figs. 1 and 2 the tappet wheel or disk is of double construction having the spaced parallel elements 26^a and 26^b in which the arms of the yoke 27 operate, said tappet member carrying tappets 32 for successive engagement with the contact 33 on the yoke of the hammer or plunger. Also as illustrated in Figs. 70 1 and 2 the said contact may be provided with a cushion spring 34 to relieve the jar incident to the successive engagement of the tappet with the contact and which serve to successively retract the hammer against the 75 tension of the spring 31 and then intermittently release the same to permit the spring to force the hammer or plunger into contact with any suitable tool bit which may be carried in the tool socket 35.

From the foregoing description it will be obvious that the arrangement of the parts is simple and the construction of motion direct, and all of the frictionally contacting parts are within the zone of the blast of the 85 ventilating fan so as to be kept at a suitable operative temperature. The communication of motion from the motor to the tappet member is through a gearing which acts directly and is devoid of unnecessary complication.

In the modified form of tappet and hammer yoke illustrated in Figs. 4 and 5 the arms of the yoke are split as shown more clearly in Fig. 5, a single disk constituting 95 the tappet member as shown at 36, and in this form anti-friction sleeves 37 are arranged upon the contacts 38 whereas in the form illustrated in Figs. 1 and 2, the preferred antifriction relation between the 100 parts is secured by providing the tappets 32 with anti-friction sleeves or rollers 32^a.

Also in the modification illustrated in Figs. 6 and 7 the yoke has its arms split or divided to arrange the elements thereof on 105 opposite sides of an intermediate single tap-

pet disk 39 of which the tappets 40 are provided with anti-friction sleeves 41 for engagement with the contact 42 of the hammer yoke 43.

5 Moreover, as a further means for guiding the hammer or plunger, particularly as illustrated in the form shown in Figs. 1 and 2, longitudinal webs 44 may be disposed upon the inner surface of the casing to engage the 10 side surfaces of the yoke arm, but it is obvious that any equivalent of this arrangement of the parts may be adopted as found most convenient.

From the above description it will be 15 noted that the frictional contact and jar incident to the relative movement of the tappet member and yoke of the hammer or plunger are minimized, so that the full effect of the power of the motor may be utilized in the 20 operation of the hammer, the successive

blows of which are determined in force by the tension of the impelling spring which is compressed successively by the co-operative action of said tappet and the yoke.

What is claimed is:—

A device of the class described including a reciprocating spring impelled plunger, a yoke carried by one end thereof and provided with a contact, a rotary tappet carrying member, tappets arranged on said member for successive engagement with the contact of the yoke, a cushion spring associated with the contact of the yoke to relieve the jar incident to the successive engagement of the tappets with said contact, fixed guides, 30 and the arms of said yoke being channeled to receive said guides.

In testimony whereof I affix my signature.

SAMUEL W. M. KOLLOCK.
